UNITED STATES PATENT OFFICE.

FRANK DAVIS, OF NORTH ADAMS, MASSACHUSETTS.

DOOR-LOCK.

1,239,360.

Specification of Letters Patent. Patented Sept. 4, 1917.

Application filed June 5, 1917. Serial No. 172,954.

To all whom it may concern:

Be it known that I, FRANK DAVIS, a citizen of the United States, residing at North Adams, in the county of Berkshire and 5 State of Massachusetts, have invented new and useful Improvements in Door-Locks, of which the following is a specification.

This invention relates to door locks, and embodies a sliding bolt and actuating means 10 therefor of novel construction, the lock being simple in its make-up, including few parts whose disposition and association are such that an efficient mechanism is produced, which can be both readily installed in the 15 door and easily manipulated.

The nature and advantages of the invention will be better understood when the following detail description is read in connection with the accompanying drawing, the 20 invention residing in the construction, combination and arrangement of parts as claimed.

In the drawing forming part of this specification like numerals of reference indicate 25 similar parts in the several views and wherein:—

Figure 1 shows a fragmentary sectional view of the door with my improved lock associated therewith in side elevation.

Fig. 2 is a horizontal sectional view taken 30 through the door and lock casing, looking down on the lock mechanism.

Fig. 3 shows the component parts of the lock separated.

Referring more particularly to the drawing in detail 10 indicates the door casing, the door being indicated at 11 and provided with the usual recess 12 for the reception of the lock casing. In accordance with my invention the lock casing is of cylindrical formation as indicated at 13, the casing being coextensive in length with the length of the recess 12, and in which casing is arranged the component parts of the lock mechanism.

The lock mechanism embodies a sliding bolt 14 movable within the casing 13 and adapted to be projected beyond one extremity thereof into an opening or recess 15 in the door casing 10 as clearly shown in Fig.

1. The bolt also operates through a member 16 which is of substantially cylindrical formation, and having the major portion of its length snugly fitted within the casing 13 adjacent the forward extremity thereof, the member 16 serving to guide the bolt 14 in its movements to an active or inactive posi-

tion. The member 16 is provided with a flange 17 which bears against the forward extremity of the casing 13, the periphery of the flange being also beveled as at 18 and 60 counter-sunk to lie flush with the jamb of the door 11. If desired a set screw 19 may be employed to maintain the member 16 fixed, relative to the casing 13. Projecting rearwardly from the member 16 is an arm 65 20, which is equidistantly spaced from the sides of the casing, and formed adjacent one end with spaced parallel apertured lugs 21 uprising from the arm 20. The lugs 21 provide bearings for a collar 22 which is fitted 70 between the lugs for rotation, the collar 22 being provided with an opening 23 of rectangular formation in cross section for the reception of a stem 24 of similar cross sectional configuration, the stem 24 forming 75 part of a key having an enlarged finger gripping portion 25. The stem 24 passes through the openings 23 in the collar, and also through aligned openings 26 in the casing 13 which is disposed in registry with the 80 opening 23. The stem 24 is suitably mounted for rotation, and it is manifest that when the manipulating portion 25 is turned in one or the other direction to rotate the stem 24, a similar movement will be im- 85 parted to the collar 22 as the latter is fixed upon the stem for rotation therewith. The stem 24 is provided with an enlargement 27 which is snugly fitted within one wall of the recess 10 as clearly illustrated.

Embracing the collar 22 medially there- 90 of, and also secured thereto in any suitable manner is a ring 28 which as shown in Fig. 2 is interposed between the lugs 21 of the arm 20. The ring 28 is provided with an 95 offset eye member 29 in which is fitted the angular extremities 30 of a substantially U-shaped wire yoke 31 the cross piece 32 of which is passed loosely through an opening 33 in the bolt 14, whereby the yoke is 100 swingingly associated with the bolt and also pivotally connected with the ring 28. Mani- 105 festly when the stem 24 is rotated in one direction, the collar 22 being fixed upon the stem for rotation therewith is also moved to retract the bolt 14 from the re- 110 cess 15, through the instrumentality of the yoke 31. Again should the stem be rotated in an opposite direction, the movement of the enumerated parts are reversed to ex- 115 tend the bolt 14 to an active position. It will now be noted, that the stem 24 is ac-

tuated only from the inside of the door, and if desired the key in its entirety including the stem 24 can be removably fitted in place, so that subsequent to the adjustment of the 5 bolt 14 to either an active or an inactive position, the key can be removed from the door. The mechanism is not only simple in construction, and positive in operation, but from the disclosure of Fig. 3 it will be ob- 10 served that the component parts of the mechanism can be quickly and easily assembled, or disassembled as the occasion may require, subsequent to the extraction of the casing 13 from the recess 12.

15 While it is believed that from the foregoing description the nature and advantages of the invention will be readily apparent, I desire to have it understood that what is herein shown and described constitutes one 20 embodiment of the invention, which I do not consider restrictive, and that such changes in the construction and arrangement of parts may be resorted to when desired as fall within the scope of what is claimed.

25 What is claimed is:—

1. A lock embodying a casing, a bolt 30 slidable therein, and adapted to be projected

beyond one end thereof, a guiding element fitted within the casing and through which said bolt reciprocates, an arm projecting 35 rearwardly from said guiding element, spaced apertured lugs rising from said arm, and constituting bearings, a rotatable element extended through said lugs, a collar fixed upon the rotatable element and jour- 40 naled between said bearings, and a connection between said collar and the bolt whereby the latter is reciprocated upon rotation of the said element in a reverse direction.

2. A door lock embodying a casing adapt- 45 ed to be fitted within a mortise in said door, a bolt arranged to slide within the casing, a hollow tubular member closing one end of the casing and constituting a guide for the bolt, an arm projecting rearwardly from 50 said guide, said arm being wholly disposed within the casing and spaced therefrom, and means supported upon the extremity of said arm and associated with said bolt for controlling the movements thereof to an active and inactive position.

In testimony whereof I affix my signature.

FRANK DAVIS.
